US0D1112310S

(12) **United States Design Patent** (10) **Patent No.:** **US D1,112,310 S**
Bae et al. (45) **Date of Patent:** **** Feb. 10, 2026**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Soojung Bae**, Suwon-si (KR); **Seoyeon Kim**, Suwon-si (KR); **Sugyeong Kim**, Suwon-si (KR)

(73) Assignee: **SAMSUNG ELECTRONICS CO., LTD.**, Suwon-si (KR)

(**) Term: **15 Years**

(21) Appl. No.: **29/976,858**

(22) Filed: **Dec. 4, 2024**

(30) **Foreign Application Priority Data**

Jun. 11, 2024 (KR) 30-2024-0022685

(51) **LOC (15) Cl.** **14-04**

(52) **U.S. Cl.**

USPC **D14/485**; D14/488

(58) **Field of Classification Search**

USPC D14/485-488

CPC H04M 1/724-72484; G06F 3/048; G06F 3/0482; G06F 3/04817

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter shown by a pair of dashed broken lines in the FIGURE illustrates a display screen or portion thereof that forms no part of the claimed design. The remaining dashed broken lines in the drawing illustrate portions of the graphical user interface that form no part of the claimed design.

1 Claim, 1 Drawing Sheet
